Charles L. Wright

UNITED STATES PATENT OFFICE.

RAGNVALD LELAND, OF BIRCH HILLS, SASKATCHEWAN, CANADA.

FLYTRAP.

1,386,415.

Specification of Letters Patent. Patented Aug. 2, 1921.

Application filed April 27, 1920. Serial No. 377,026.

To all whom it may concern:

Be it known that I, RAGNVALD LELAND, a subject of the King of Norway, and a resident of Birch Hills, in the Province of 5 Saskatchewan, Canada, have invented certain new and useful Improvements in Fly-traps, of which the following is a specification.

The main object of this invention is to 10 provide an appliance adapted to lure, entrap and exterminate insects, particularly flies, such as infest human habitations, to the detriment of food and discomfort of individuals.

15 A further object is to provide such appliances in forms inexpensive to construct, capable of long service, easy and simple to operate and effective in producing results.

These objects are attained by the novel 20 construction, combination and arrangement of parts hereinafter described and shown in the accompanying drawings, forming a material part of this disclosure, in which:—

Figure 1 is a plan view of a fly trap made 25 in accordance with the invention.

Fig. 2 is a longitudinal sectional view taken on line 2—2 of Fig. 1.

Fig. 3 is a side elevational view of the same, the trap being shown in a closed 30 position.

Referring to the drawings in detail, the numeral 10 designates a flat level base plate having a raised right angled end wall 11, from the upper edge of which extend a pair 35 of outwardly projecting arms 12 having a space 13 between them and supporting a bar 14 at their extremities.

A single arm 15 is curved upwardly and outwardly from the opposite end of the plate 40 10, this arm being slotted at its outer end, presenting forks in which is engaged another bar 16, all of the several arms being doubled or otherwise reinforced to provide adequate rigidity.

45 A rod 18 is disposed longitudinally over the center of the plate, the rod being secured by an angular foot 19, soldered or otherwise fastened to the raised end plate or abutment 11, while at the other end the rod is bent 50 down and out, presenting another foot 20 secured in a similar manner to the plate 10 near its head end, the rod constituting a guide or trackway.

An open hollow rectangular slide 22, com-

prised of a cover, rear and end walls, is 55 slidably mounted on the rod 18, the same passing through the rear wall, the lower edge of which is in close sliding contact with the upper surface of the plate 10.

Attached to the center of the slide, is a 60 bracket 23 having outward and upward extending arms 24 inclosing a space 25 and carrying a bar 26, to which is attached one 65 end of a tensional element 28, which may be an elastic tape, or helical spring as shown, the other end of the element being engaged to the bar 14. The spring passes freely through the openings 13 and 25, normally drawing the slide 22 to the foot of the device, into contact with the end plate 11 which 70 forms a closure to the hollow slide.

Also pivoted on the bar 26 is a detent hook or trigger 30 adapted to engage the bar 16 when the slide is retracted or drawn against the pull of the tension element 28 75 to the head end of the plate.

In operation, a thin film 32 of syrup or other substance adapted to act as a lure or attraction for the insects is disposed on the surface of the plate 10, either before or after the slide 22 has been drawn out to its limit and the detent hook 30 engaged with the fixed bar 16.

When the flies or other insects have settled upon the plate 10, in any considerable 85 number, the hook is manually released from the bar 16, permitting the spring 28 to actuate the slide 22 which is drawn violently over the plate, sweeping its surface and confining the insects within the slide, then against the plate 11, until such time as is convenient to dip the lower end of the plate 90 and slide in boiling water, to destroy the life of the flies, which can then be removed in any convenient manner, whereupon the 95 appliance is ready for resetting.

The film or films of syrup are not necessarily disturbed by the movement of the slide and may be used indefinitely, while obviously the implement can be readily moved 100 at will and used as required, soon clearing a room or apartment of the nuisance and pest of flies so objectionable.

This disclosure is, however, to be regarded as descriptive rather than restrictive or limitative of the invention, of which obviously other embodiments may be constructed, including minor structural changes and modi-

fications, without departing from the general scope herein indicated and denoted by the claims which are appended.

I claim—

5 1. A fly trap comprising a flat base plate adapted to receive a fly attracting substance, a raised abutment wall at one end thereof, a hollow slide having an open side adapted to be closed by said wall when thereagainst,
10 tensional means for drawing said slide against said wall, a stiffening rod rigidly attached at its ends to said plate and extending centrally longitudinally thereover, the rod passing freely through said slide, and
15 releasable means for holding said slide when extended.

2. A fly trap comprising a level base plate, a slide movable thereover, an abutment forming a closure for said slide, a guide on
20 said plate for said slide, overhanging arms

on said abutment and slide respectively, tensional means secured to said arms, and a pivoted hook carried by said slide engageable with the end of said plate opposite said abutment and releasable therefrom.

3. A fly trap comprising a base plate, an end wall raised therefrom, an arm extending outwardly from said wall, an arm extending from the opposite end of said plate, a rod secured to said plate extending longitudinally thereover, a hollow slide movable on said rod forming coöperatively with said wall a container, tensional means extending between the first named arm and said slide, and a pivoted detent hook carried by said slide engageable with said second arm.

In testimony whereof I have signed my name to this specification.

RAGNVALD LELAND.
